(57) **CLAIM**

The ornamental design for a container bottom, as shown and described.

DESCRIPTION

FIG. 1 is a top perspective view of a container bottom showing my new design;

FIG. 2 is another top perspective view thereof;

FIG. 3 is a left elevational view thereof, the right being a mirror image;

FIG. 4 is a top plan view thereof;

FIG. 5 is a front elevational view thereof, the back being a mirror image;

FIG. 6 is a bottom plan view thereof;

FIG. 7 is a bottom perspective thereof;

FIG. 8 is a cross-sectional view thereof, taken along line 8—8 of FIG. 4; and,

FIG. 9 is a cross-sectional view thereof, taken along line 9—9 of FIG. 4.

The container lid shown in broken lines represents unclaimed subject matter and forms no part of the claimed design.
